UNITED STATES PATENT OFFICE.

GEORGE MILLER AYLSWORTH, OF COLLINGWOOD, ONTARIO, CANADA.

RADIATOR.

981,519.

Specification of Letters Patent. Patented Jan. 10, 1911.

Application filed January 13, 1910. Serial No. 537,807.

To all whom it may concern:

Be it known that I, GEORGE MILLER AYLSWORTH, a subject of the King of Great Britain, and a resident of Collingwood, in the 5 Province of Ontario and Dominion of Canada, have invented a new and Improved Radiator, of which the following is a full, clear, and exact description.

My invention has for its object to provide 10 a radiator which will not take up any of the floor space in a room, and one which will not disfigure the walls, while it will permit a full flow of air from the room around the radiator and back again to the room.

15 Another object of the invention is to so arrange the device that there is no danger of the entrance of smoke, dust or ashes into the room, and to so dispose the radiator that the possibility of the walls and the decorations 20 of the room being soiled by dust from the floor, which has become heated, will be reduced to the minimum.

Other objects are to so arrange and assemble the parts that the ordinary construction 25 of the wall in which the radiator is disposed is not materially altered, and to provide a radiator, the cost of which will be about one-quarter the cost of cast iron radiators, such as are now on the market.

30 Still another object of the invention is to so reinforce and construct the walls of the radiator that they may be made much thinner than in other constructions, thus assuring the most conductivity and the most economical results. As the walls of the 35 radiator assure greater conductivity of the heat, it is unnecessary to have a large, exposed surface or a number of turns in the radiator conduit.

40 Still other objects of the invention will appear in the following complete description.

In this specification I will describe the preferred form of my invention, it being understood 45 that the scope of the invention is defined in the appended claims.

Reference is to be had to the accompanying drawings forming a part of this specification, in which similar characters of reference indicate corresponding parts in all the 50 views, and in which—

Figure 1 is a perspective view, showing a portion of the interior of the room and the wall in which my radiator has been disposed; Fig. 2 is a side elevation of the wall 55 in which one of my radiators is disposed, a

portion of the wall being broken away to show the arrangement of the radiator; Fig. 3 is a transverse, sectional view of the wall in which a radiator is disposed; Fig. 4 is a 60 sectional view on the line 4—4 of Fig. 2; and Fig. 5 is a perspective view showing a fragment of a copper plate and the iron reinforcing.

By referring to the drawings it will be 65 seen that in the wall 5 there are spaces between the studs 6 and 7, the stud 7 having an opening therethrough, connecting the spaces at either side. Rods 8 are provided which connect the studs, and around these rods 70 there are disposed two sheets of copper plate 9, one of the sheets of copper plate 9 being situated at each side of the stud 7. The rods are disposed in groups of three 75 each, the upper rod 8 serving to support the sheets of copper plate 9, which are looped, and the two lower rods 8 serving to separate the front and rear walls of the copper plate 9. The same construction is provided for each side of the central stud 7. The edges 80 of the sheet of copper plate 9 are bent to form flanges 10, and members 11 constructed preferably of tin, are disposed at each side of each of the copper plates 9, the members 11 connecting the flanges 10 and being bent 85 thereover to hold the sides of the copper plates in position. These flanges 10 and the terminals 12 of the members 11 which are bent over the said flanges, are secured to the studs 6 and 7 by means of nails 13, strips of 90 asbestos 14 being disposed between the members 11 and the studs 6 and 7. Around the opening 15 in the central stud 7, there are disposed strips of asbestos 16, which are continued from the asbestos strips 14 disposed 95 at the sides of the central stud 7. One member 11, at the top of the stud 7 runs down along one of its sides, through the opening 15 and up its other side, while the other member 11 is continued upwardly at one side 100 of the stud 7, through the opening 15 and down the other side.

When the members are constructed and are assembled as has been described, it will be seen that there is a conduit, which rises 105 at one side of the central stud 7, which passes through the said central stud and which extends downwardly at the other side of the said central stud 7, the said passage or conduit being formed by the copper plates 9 and the members 11, the copper plates 9 and the said members 11 being separated 110

from the studs 6 and 7 by the asbestos strips 14 and 16. To the top and the bottom of the copper plates 9 are secured iron reinforcing members 17, the terminals 18 of the 5 said reinforcing members 17 being bent over to form flanges in contact with the flanges 12 of the copper plates 9, the said terminals 18 of the iron reinforcing members 17 being secured to the studs 6 and 7 with the 10 said flanges 12. Rising through the floor 19, there are two pipes 20, one of which is connected with the terminals of each of the copper plates 9 by connecting members 21, there being dampers 22 disposed in the 15 connecting members, so that communication between the pipes 20 and compartments 23 formed by the copper plates 9, may be cut off when desired. The pipes 20 are connected with a hot-air furnace (not shown). 20 The walls formed by the copper plates 9 are disposed at distances from either side of the wall 5, to permit of the passage of air between the inner sides of the said walls 5 and the outer sides of the copper plates 9. 25 These passages 24 between the copper plates 9 and the inner sides of the wall, are connected with the room near the floor by an opening 25 which permits the air from the room to pass between the inner sides of the 30 wall and around the compartments 23 formed by the copper plates 9. Inasmuch as the sides of the connecting members 21 converge downwardly, the air entering the opening 25 may pass the connecting members, as at 26, to the rear of the compartments 23. Above the plane of the upper rod 8, there is another opening 27, which leads into the room, there being a deflecting plate 28 which is secured to the studs 6 and 7, and 35 40 which is adapted to direct, through the opening 27, the air which rises around the compartments 23 and becomes heated in consequence.

As has been stated, the pipes 20 are connected with a hot-air heater, the hot air rising in one of the pipes 20, as shown by the arrows, entering one of the compartments 23, passing through the opening in the central stud 7 into the other compartment 23 and thence downwardly through the pipes 20 to become re-heated in the usual way by the furnace.

By means of the handles 29, the dampers 22 may be closed or be opened, as desired, 55 thereby regulating the hot air passing into and through the compartments 23 formed by the copper plates 9 and the members 11. As the copper plates 9 become heated by the hot air, they heat the air in the passages 60 24 which causes it to rise and pass into the room through the openings 27, thereby creating a circulation of air through the openings 25, through the passages 24, around the compartments 23 and out through the 65 openings 27 into the room. The openings

25 and 27 are preferably covered by metal plates 30, having openings to permit the air to pass therethrough.

Having thus described my invention, I claim as new and desire to secure by Letters 70 Patent:

1. In combination with a wall having studs spaced apart and provided with two openings, one of the studs having an opening therethrough, and conduit members disposed at each side of each end of the opening in the stud and connecting the stud having the opening with two neighboring studs, forming compartments, which are connected by the opening in the stud, the two 80 openings in the wall leading to the space surrounding the compartments.

2. In combination with a wall having studs spaced apart in alinement and provided with two openings, one of the studs 85 having an opening therein, conduit members disposed at each side of each end of the opening in the stud and connecting the stud having the opening with two neighboring studs, forming compartments, which are connected by the opening in the stud, the two 90 openings in the wall leading to the space surrounding the compartments, and a damper commanding a passage formed by the conduit members.

3. In combination with a wall having three studs spaced apart and disposed in alinement, the central stud having an opening, two sheets of material, one disposed at each side of the central stud having the 100 opening, each of the two sheets of material being bent, with its body at one side of its bent portion disposed substantially parallel with its body at the other side, the sheets of material being disposed around the opening in the central stud and extending from the central stud to the neighboring studs respectively, the sheets of material being secured to the studs, forming two compartments, which are connected by the opening 110 in the central stud, the ends of the sheets of material being spaced from each other respectively, to permit the flow of a heating medium through the compartments.

4. In combination with a wall having 115 sides, with a space therebetween, and studs disposed in the space, a sheet of material disposed in the space in the wall, the sheet of material having flanges at its sides, and members connecting the flanges, the sides of 120 the members being bent over and being secured to the flanges and to the studs, the sheet of material and the said members forming a compartment, the ends of the sheet of material being spaced from each other to permit the flow of a heating medium into the compartment.

5. In combination with a wall having two studs spaced apart and disposed in alinement, the wall being provided with an open- 130

ing, a sheet of material connecting the studs, the sheet of material being bent and having two portions which are spaced apart and are disposed substantially parallel to each other, and members connecting the sides of the sheet of material at the studs, the sides of the sheet of material being secured to the last-mentioned members and to the studs forming a compartment, the ends of the sheet of material being spaced from each other to permit the flow of a heating medium into the compartment.

6. In combination with a wall having two studs, rods connecting the studs, and a sheet of material disposed between the studs and around the rods, the sides of the sheet of material being secured to the studs respectively, forming a compartment, the ends of the sheet of material being spaced from each other to permit the flow of a heating medium into the compartment.

7. In combination with a wall having two studs spaced apart, a sheet of material disposed between the studs having flanges at its sides, the sheet of material being bent, with its body at one side of its bent portion disposed substantially parallel with its body at the other side, and members extending at each side of the sheet of material, from its body at one side of its bent portion to its body at the other side, the sides of the members being bent over on the flanges and being secured to the studs, the sheet of material and the said members forming a compartment braced by the studs, the ends of the sheet of material being spaced from each other to permit the flow of a heating medium into the compartment.

8. In combination with a wall having three studs spaced apart, the central stud having an opening, two sheets of material, one disposed at each side of the central stud, the sheets of material having flanges at their sides and being bent, with their bodies at one side of their bent portions disposed substantially parallel with their bodies at their other sides respectively, and members extending across the sides of the sheets of material respectively, and bent over on the flanges and secured to the studs and around the opening in the said stud, the sheets of material and the said members forming a conduit braced by the studs, through which a heating medium may flow.

9. In combination with a wall having three studs spaced apart and provided with two openings, there being an opening in the central stud, two sheets of material, one disposed at each side of the central stud, the sheets of material having flanges at their sides and being bent, with their bodies at one side of their bent portions disposed substantially parallel with their bodies at their other sides respectively, and members extending across the sides of the sheets of material respectively, and bent over on the flanges and secured to the studs and around the opening in the said stud, the sheets of material and the said members forming a conduit braced by the said studs, through which a heating medium may flow, the two openings in the wall leading to the space around the conduit.

10. In a radiator, supporter members, a sheet of material disposed between the supporter members and having flanges at its side, the sheet of material being bent, with its body at one side of its bent portion disposed substantially parallel with its body at the other side, and members extending at each side of the sheet of material, from its body at one side of its bent portion to its body at the other side, the sides of the members being bent over on the flanges and being secured to the supporter members, the sheet of material and the said members forming a compartment braced by the supporter members, the ends of the sheet of material being spaced from each other to permit the flow of a heating medium into the compartment.

11. In a radiator, supporter members, rods connecting the supporter members, and a sheet of material disposed between the supporter members and around the rods, the sides of the sheet of material being secured to the supporter members respectively, the ends of the sheet of material being spaced from each other to permit the flow of a heating medium between the walls of the sheet of material.

In testimony whereof I have signed my name to this specification in the presence of two subscribing witnesses.
